GRINDING WHEEL

Leo F. Carr, Painesville, Ohio

Application June 11, 1945, Serial No. 598,876

3 Claims. (Cl. 51—209)

1

The present invention relates to improvements in grinding wheels, and has particular reference to wheels of bonded abrasive material having a circumferential end face about a central opening.

One of the objects of the present invention is to provide a novel end face grinding element which has a rapid cutting action and which is adapted for heavy duty operation.

Another object is to provide a new and improved end face grinding wheel which has a non-circular center opening, and which is formed in a unitary or single-piece structure closed throughout the circumference.

A further object is to provide a novel abrasive grinding wheel which has a continuous end face about a non-circular center opening operative to hold and agitate the liquid coolant and to direct the latter to the surface being ground.

Other objects and advantages will become apparent as the description proceeds.

In the accompanying drawings,

Figure 1 is an outer end face view of a grinding wheel embodying the features of my invention.

Fig. 2 is a diametrical sectional view of the wheel taken along line 2—2 of Fig. 1.

Fig. 3 is a fragmentary sectional view, on an enlarged scale, taken along line 3—3 of Fig. 1.

Referring more particularly to the drawings, the grinding wheel, constituting the exemplary embodiment of the invention, comprises a rotary grinding element 1 made of bonded abrasive material adapted to wear or break away in use. The element 1 is of the general type having a completely closed peripheral wall defining a narrow circumferential end face 2 about a central recess or opening 3. Although not limited to any particular size or use, this type of wheel usually is made comparatively large in size, and supported for relative transaxial movement in a shear cut across the surface of the work in heavy metal removing operations.

Conventional ring wheels heretofore have been provided with a concentric cylindrical opening defining an annular end grinding face of uniform radial width throughout the circumference. In such construction, the grinding face has a uniform resistance to wear throughout its area, and all of the circular lines of cut are continuous and uninterrupted. Liquid coolant supplied to the central opening can enter between the grinding face and the surface being ground only in small amounts and with difficulty. By reason of these factors, the rate and efficiency of the cutting action are considerably impeded, and the work is not always finished with the desired degree of surface smoothness.

The grinding element 1 of the present invention preferably also has a continuous or uninterrupted external cylindrical surface 4, but is provided with a central opening 3 of non-circular

2

shape. Within the broad aspects of the invention, various non-circular shapes may be employed provided they are symmetrical and centrally located to afford dynamic balance. Preferably, the opening 3 is multi-sided, for example with three or more straight sides suitably joined at the contiguous ends to provide corner areas projecting radially outwardly across the innermost circular lines of cut. More particularly, the opening 3, in the specific form shown, is substantially square, with four straight flat sides 5.

The square center opening 3 materially influences the shape and cutting characteristics of the circumferential end face 2. Thus, each of the sides 5 of the center opening 3 is a chord of the outside cylindrical periphery, and coacts with the latter to define a narrow externally arcuate face segment 6 of varying width. The width is the greatest at the center and decreases progressively toward opposite ends of each segment 6. The extreme ends of the segments 6 are integrally connected or joined at the corners of the opening 3, thereby producing the grinding element 1 in one piece entirely closed throughout the external periphery. The connected ends of the segments 6 also define the narrowest areas 7 of the grinding face 2.

As a result of the foregoing construction, the grinding face 2, about the square center opening 3, has four uniformly spaced areas 6 of relatively large expanse and wide maximum radial dimension, and four connecting areas 7 alternated therewith, and of relatively small expanse and minimum radial dimension. The large areas 6 have a hard cutting action, and are strongly resistant to wear. Conversely, the small narrow areas 7 are comparatively weak, and much less resistant to wear or crumbling. This difference in grinding strength causes the areas 7 in use to recede from the plane of the areas 6, and thereby impart to the grinding face 2 a slightly undulating surface with four low points and four alternate high points with highly effective grinding characteristics. Although the grinding face 2 varies in width and assumes an undulating form in use, it does not have a completely interrupted cutting action, and remains in contact with the work, thereby preventing end play of the supporting spindle from injuring the work, and instead insuring a smooth flat surface finish on the work.

The foregoing results are to be contrasted from those obtained in the use of end face grinding wheels of the type in which a plurality of separate abrasive segments are secured in spaced assembled relation in a holding chuck. In such wheels, the grinding cut is completely interrupted, and hence the sharp ends of the segments are required repeatedly to move onto and off of the work surface. This causes the ends of the seg-

ments to break off or disintegrate excessively, and permits end play in the spindle to mar or impair the work surface, so that a smooth flat work surface is not obtainable.

For optimum performance, the ratio of the maximum radial dimension, for example through the center of the areas 6, to the minimum radial dimension, for example through the narrow connecting areas 7, should be as large as possible, consistent with the strength required to withstand centrifugal force, and the permissible aggregate area of the grinding face 2 for a given horsepower rating. To this end, the areas 7 preferably are made as narrow as is permissible within the strength requirements. For a given diametrical size of wheel, the maximum radial dimension of the face 2 is determined by the shape and relative size of the center opening 3. If the center opening 3 is made too small, it may interfere with the spindle mounting, particularly in wheels of comparatively small size, and may produce a grinding face that is too large and requires excessive horsepower to operate the wheel. In instances where the grinding face 2 would not be too wide as a result, the central opening 3 can be made with square corners. Preferably, however, the corners are at least slightly chamfered or beveled to facilitate manufacture and to avoid sharp angles. When required, the width of the segments 6 may be decreased to the desired maximum dimension by increasing the chamfer on the corners of the central opening. In this event, the sides 5 of the opening 3 are connected at their ends by diagonal corner surfaces 8 which may be of any desired shape, and which in the present instance are shown as arcuate and concentric to the outer peripheral surface 4. As a result, the connecting areas 7 of the face 2 between the ends of the segments 6 consist of short arcuate sections.

The abrasive element 1 has a rear mounting face 9 adapted to be secured in position against a flat supporting surface, such as the exposed face of a circular adapter plate 10. To increase the strength of the abrasive element 1, particularly at the narrow sections 7, the rear portion preferably is formed with a thin annular extended back 11 which extends into and underlies the corner portions of the central opening 3. The back 11 is provided of such a width that the side surfaces 5 of the opening 3 are substantially tangent to the inner peripheral edge 12 thereof. It will be understood that the central opening 3 extends from the outer end face 2 inwardly through the element 1 to the extended back 11.

To further strengthen the abrasive element 1 when desirable, suitable wire bands 13 may be tightly secured about the outer periphery.

Within the broad aspects of the invention, the abrading element 1 may be secured to the adapter plate 10, or other suitable support, in any desired manner. It is particularly advantageous, however, to utilize a wire anchoring means molded directly in the rear portion and extended back 11 of the element 1 since such means provides an added reenforcement greatly strengthening the element at the comparatively narrow sections 7, and consequently permitting the latter to be made narrower by reason of the increased strength than would otherwise be permissible. A suitable wire reenforcement may comprise an annular wire mesh 14 molded in the rear portion of the element 1 flush with the rear mounting surface 9 and coextensive in size therewith. A plurality of nuts 15 or other screw elements are also

molded in the abrasive element 1 in position against the inner surface of the wire mesh 14 for attaching the element coincidentally to the backing plate 10. In the present instance, the nuts 15 are arranged in uniformly peripherally spaced relation and centrally between the outer and inner edges of the rear mounting face 9. Any suitable number of nuts 15 may be provided, and, in the present instance, eight nuts are indicated, of which four are conveniently located centrally of the segments 6, and the other four are located at the abrasive sections 7 within the corners of the opening 3. The aggregate thickness of the wire mesh 14 and the superimposed nuts 15 corresponds approximately to that of the extended back 11 so that all of the abrasive can be used down to the back.

To mount the abrasive element, bolts 16 are extended through openings in the plate 10 and threaded into the respective nuts 15. The mounting or adapter plate 10 in turn is concentrically bolted to a collar 18 on a rotary spindle 19. This method of mounting the abrasive element 1 has the advantage that it not only reenforces the element at the weak points, but also avoids the use of complicated chucks, flanged rings or other holding devices which are costly in construction, and which reduce the amount of abrasive that can be worn off in use.

The peripherally closed abrasive element 1 with the square or balanced noncircular central opening 3 has another important operating advantage in that it tends to direct the liquid cooling medium between the grinding face 2 and the surface of the work being ground. In ring wheels with truly annular faces, the cooling medium, which is commonly introduced into the central opening, is confined within the circular wall of the opening, and can enter the grinding zone only with difficulty, if at all, thus tending to result in undue heating and hence of necessity requiring a slowing down of the cutting action. In wheels comprising individual segments, much of the cooling medium escapes and is lost through the open spaces between the adjacent ends of the segments. In contrast, the abrasive element 1 of the present invention confines substantially all of the coolant introduced into the central opening 3 for effective use. Also, the noncircular shape of the opening 3 tends to churn or agitate the coolant and to direct it to the grinding zone. More particularly, the coolant, under the influence of centrifugal force, tends to flow toward and into the corners of the opening 3. Hence, bodies of the coolant are piled up in direct contact with the surface of the work between and in the path of the abrasive segments, and are squeezed back and forth by the advancing segments and virtually forced into the grinding zone.

It will be evident from the foregoing that I have produced a new and improved molded abrasive grinding wheel or element with an uninterrupted end face which will remove metal by grinding at a greatly increased rate, which will utilize the cooling medium efficiently, and which will produce a flat work surface with a smooth finish.

I claim as my invention:

1. A rotary one-piece dynamically balanced abrading element of bonded abrasive material having a completely closed continuous external perimeter and a central opening in the front end, said opening being substantially square in shape and defining a continuous circumferential front

end face adapted for grinding, said face consisting of four uniformly peripherally spaced chordal segments integrally joined at their contiguous ends, said element having an inwardly extended back at the rear end defining an annular mounting face and underlying the corners of said opening which extends thereto, a wire mesh molded in said element adjacent said mounting surface and being coextensive in area therewith, and a plurality of uniformly peripherally spaced screw elements molded in said element against the inner surface of said wire mesh for securing said element to a rotary support.

2. A rotary one-piece dynamically balanced abrading element of bonded abrasive material having a completely closed continuous external cylindrical surface and a central opening extending substantially therethrough from the front end, said opening being substantially square in shape with arcuately chamfered corners and defining a continuous circumferential front end face adapted for grinding, said face consisting of four uniformly peripherally spaced chordal segments integrally joined at their contiguous ends by narrow arcuate connecting sections, said element having an inwardly extended back at the rear end defining an annular mounting face and underlying the corners of said opening adjacent said sections, the sides of said opening being tangential to a cylindrical projection of the inner peripheral edge of said extended back, an annular wire mesh molded in said element adjacent said mounting surface and being coextensive in area therewith, a plurality of uniformly peripherally spaced nuts molded in said element against the inner surface of said wire mesh and adapted to receive bolts through the rear end of said element for securing said element to a rotary support, said nuts being respectively located centrally of said segments and at the corners of said

opening, and reenforcing bands tightly encircling the outer periphery of said element.

3. A rotary one-piece dynamically balanced abrading element of bonded abrasive material having a completely closed continuous external perimeter and a central opening in the front end, said opening being non-circular and multi-sided in shape and defining a continuous circumferential front end face adapted for grinding, said face consisting of a plurality of uniformly peripherally spaced chordal segments integrally joined at their contiguous ends, said element having an inwardly extended back at the rear end defining an annular mounting face and underlying the corners of said opening which extends thereto, a wire mesh molded in said element adjacent said mounting surface and being coextensive in area therewith, and a plurality of uniformly peripherally spaced screw elements molded in said element against the inner surface of said wire mesh for securing said element to a rotary support.
